DIRECTIONAL ANTENNA ARRAY

Andrew Alford, New York, N. Y., assignor to
Mackay Radio and Telegraph Company, New
York, N. Y., a corporation of Delaware

Original application April 30, 1937, Serial No.
140,039, now Patent No. 2,195,880, dated April
2, 1940. Divided and this application Septem-
ber 29, 1939, Serial No. 297,063

2 Claims. (Cl. 250—11)

This invention is a division of my copending application 140,039 filed April 30, 1937, and relates to directional antenna arrays and pertains more particularly to antenna arrays utilizing a parasitic reflector and adapted for the transmission of a plurality of different frequencies at the same time.

It is an object of my invention to provide an antenna array which is simple in construction and still is adapted for the transmission of a plurality of different frequencies either simultaneously or separately.

Heretofore it has been customary to use the so-called dipole or half-wave antenna for the transmission of only a single frequency. In fact 15 the very name of the antenna itself, expresses the thought that it is to be used for a single frequency only. But such antennae are, in truth, not extremely sharp in their transmitting qualities being, on the other hand, relatively aperiodic 20 and adapted for the transmission of a fairly wide band of frequencies. The only difference between 25 an antenna when it is operated as a true half-wave or dipole antenna and when it is energized with a frequency different from a half-wave value lies in the impedance which the antenna presents to the transmission line. In the case where the 30 radiated frequency is such that half-wave operation results, the impedance presented by the antenna to the transmission line is resistive whereas if a different frequency is transmitted the impedance will contain a capacitative or inductive component. But if proper provision is made for the matching of the antenna to the transmission 35 line over the range of frequencies which it is desired to transmit, it will be found that the so-called half-wave type antenna, consisting of two equal halves fed at the center by means of a two-wire transmission line, may be operated in an efficient manner over at least a two to one 40 range of frequencies.

Just as directional arrays may be constructed of a number of half-wave elements, so can they also be constructed of similar elements of other than a half-wave length. For the sake of simplicity such antennae as last mentioned will be called pseudo half-wave antennae or pseudo half-wave elements. A number of pseudo half-wave elements may be arranged in line and be fed in phase so as to produce a highly concentrated but a bi-directional radiation pattern. Unlike the ordinarily accepted half wave devices of the prior art, such an array is adapted for the transmission of two or three or more preselected frequencies. Generally speaking, an array of this 55

kind would have a maximum gain at that frequency at which the length of the individual pseudo half-wave element would be in the neighborhood of 1.2 wavelengths and would be somewhat less at all other frequencies. The decrease in gain with a change in frequency starting from the frequency of maximum gain is rather slight.

The main advantage of this multi-frequency array is relatively high gain per unit space, while a disadvantage is the fact that the array is bi-directional. This latter disadvantage is particularly serious when a directional array is to be used at the higher frequencies and for communication over relatively long distances. The bi-directional character of the radiation frequently results in the so-called echo difficulties.

In order to reduce the back radiation of a multi-frequency array of pseudo half-wave elements it is necessary to provide a suitable multi-frequency reflector. While it is possible to install another multi-frequency array directly in back or directly in front of the first array and identical to it, and feed it in such a way that the radiation in the backward direction will be completely cancelled, I prefer, in accordance with my invention, to utilize a parasitic reflector. By the use of a parasitic reflector the difficulty of supplying a feeding system for the second or reflecting array, is avoided.

The usual type of parasitic reflector, consisting simply of a length of wire slightly longer than an electrical half-wavelength, is not suitable for use in a multi-frequency array since this type of reflector will function at one frequency only.

In accordance with my invention I provide a pseudo half-wave antenna which is associated with a novel type of reflector, the latter being adapted to operate at a plurality of different frequencies. This reflector instead of being a single length of wire slightly longer than an electrical half-wavelength, is similar to the pseudo half-wave antenna, consisting of two equal halves connected to a sharp balancing or phase adjusting section of transmission line at the center, the two halves having an over-all length which is about the same as that of the pseudo half-wave antenna itself. The balancing or phase adjusting transmission line is provided with auxiliary wires which may be either of the short circuit or open circuit type to insure the correct phase relationship of the reflected waves at the several frequencies which it is desired to transmit.

The above mentioned and further objects and advantages of my invention and the manner of attaining them, will be more fully explained in

the following description taken in conjunction with the accompanying drawings; in which Fig. 1 shows a pseudo half-wave antenna; Fig. 2 is a field strength curve for such an antenna; Fig. 3 is a diagram used in explaining the operation of an antenna according to my invention; Figs. 4, 5 and 6 are forms of pseudo half-wave dipoles; Figs. 7 and 8 are end-on arrays of such dipoles; Figs. 9, 10 and 11 are reflector structures according to my invention, suitable for operation at several frequencies and Figs. 12 and 13 are curves showing the relation of impedance to the square of the field strength for the reflectors.

Fig. 1 shows a pseudo half-wave antenna fed with a source of unit power 2. The antenna impedance is assumed to be matched at a given frequency by the matching device 3 to the surge impedance of the transmission line and the impedance of the source of unit power 2 is assumed to be the same at all frequencies. When the arrangement in Fig. 1 is operated at a number of different frequencies it will be assumed unless otherwise stated, that the matching device 3 is such that the antenna impedance remains matched to the transmission line at each frequency. Under the assumed conditions the pseudo half-wave will radiate, if the resistance of the wires is neglected, a unit of power at each frequency.

Then, if an antenna of length L were in space so that the effects of ground reflection could be neglected, the field produced by the antenna at a distant point located in the plane bisecting the antenna at right angles would vary with frequency in the manner shown in Fig. 2. In this figure the abscissa L/λ is the overall length of the antenna in terms of wavelength and is thus proportional to frequency. The ordinate is proportional to the field strength at the distant point.

Fig. 2 clearly shows that the pseudo half-wave antenna is per se capable of producing comparable field strength at the distant point over a wide range of frequencies.

When the ohmic resistance of the conductors is considered this range of frequencies over which the antenna can function successfully is somewhat reduced. Indeed when L/λ is less than .5 the radiation resistance on a current loop basis falls rather rapidly as L/λ is decreased, with the result that the currents produced by the unit power in the section of transmission line between the antenna and the matching device 3 is increased. The current in the matching device 3 also increases. Thus for a given power delivered to the antenna the I^2R losses increase as L/λ decreases so that for very small values of L/λ the field produced at the distant point falls off and approaches zero. With the usual type of construction this decrease in radiation efficiency does not take place immediately upon a decrease of L/λ below .5, but takes place gradually and may be considered to be relatively small when L/λ is more than .25.

Thus in actual practice a pseudo half-wave antenna may be considered to be an efficient radiator from L/λ of say .3 up to $L/\lambda=1.45$ or almost a 5:1 frequency range. Over a two to one frequency range from .7 to 1.4 it is always more efficient than a half-wave.

When the antenna has been installed at a certain height above ground the effective range of frequencies which may be used for communicating with a given point may be still further reduced under certain circumstances because the

maximum of radiation may take place at the desired angle to the horizon at one frequency and at some other undesired and ineffective angle at a second frequency. When the two frequencies are used for communication with two different points which are approximately on the same great circle this may or may not be true. This situation is common to all kinds of antennae operated at more than one frequency and is not a peculiarity of the pseudo half-wave antennae or pseudo half-wave arrays, and it need not be discussed here in detail.

The pseudo half-wave antennae which have lengths between $.8\lambda$ and 1.40λ are particularly useful as elements in arrays because they result in greater signal strength at the distant point per feeder.

In order that the action of these pseudo half-wave antennae in arrays may be more clearly understood the following elementary explanation of the action of such an antenna with $L/\lambda>1.0$ is offered.

It is well known that the field produced at the distant point by an array consisting of two half-wave antennae which are fed individually and placed end-on as shown in Fig. 3 depends on the distance S between the half-wave elements. For small values of S the mutual impedance between the elements tends to reduce the currents produced in the half-wave elements by a unit of power and thus decreases the field at the distant point. For small values of S the field at a distant point increases as S is increased.

A pseudo half-wave such as shown in Fig. 4 has a current distribution which is very similar to that of two separate half-wave antennae shown in Fig. 3. The only difference between the two current distributions is the additional current in opposite phase indicated by the shaded area in Fig. 4. When distance S is relatively small the current in the shaded areas is also small and the field produced by this current at the distant point is likewise quite small. This field, however, tends to oppose the field produced by the main radiating portion of the structure. Thus as L is increased beyond 1.0λ , at first the effect is to decrease the mutual impedance between the two halves of the antenna and thus to increase the field produced at the distant point by a transmitter of unit power. When L is still further increased the radiation from the shaded area in Fig. 4 becomes appreciable and begins to cancel out the main radiation thereby decreasing the field H at the distant point. It is this phenomenon which causes the decrease of the field H when $L>1.30\lambda$. This effect may be made to take place for values of $L>1.3\lambda$ by cancelling out some of the radiation from the shaded portion in Fig. 4 by providing an auxiliary radiator 4-4 energized 180° out of phase with the main radiator, as shown in Fig. 5.

On the other hand the peak radiation may be produced for smaller values of L by loading the ends of the antenna with some form of capacity 5-5, for example as shown in Fig. 6.

When a number of psuedo half-wave antennae are operated together in an array it becomes necessary to insure that they cooperate with each other in such a way as to produce maximum field at the distant point. The exact calculation of mutual interaction between pseudo half-wave elements is rather complicated but approximately correct results may usually be obtained by considering each pseudo half-wave antenna as two separate half-wave antennae spaced a distance

$S=L-\lambda$. This assumption becomes more nearly correct when an auxiliary radiator as shown in Fig. 5 is employed. When such an auxiliary radiator is not used then the error in the calculation is due to the field produced by the auxiliary radiator. As this field is usually not very large it may be neglected in the calculation of interaction between the elements.

Thus it is found that when two pseudo half-wave antennae are connected in broadside and parallel to each other they should be about .6 to $.75\lambda$ from each other for best results. Separations between ends of $.2\lambda$ to $.6\lambda$ are found to be satisfactory when two pseudo half-wave antennae are in broadside and in line with each other.

From the above discussion it is also clear that a broadside antenna such as shown in Fig. 7, consisting of a number of sections 6, 7, 8, 9, each approximately $.64\lambda$ long, which radiates maximum energy in the plane at right angles to the antenna produces greatest radiation when the phase changers 10, 10 are so adjusted that the phase delay is about $\frac{1}{4}\lambda$ and not $\frac{1}{2}\lambda$ as is generally assumed. This type of an antenna becomes less and less aperiodic per se as the number of half-wave radiating portions is increased. Moreover, when a large number of radiating portions are employed the phase changers located further away from the ends also begin to radiate. For this reason it is probably best to use coils instead of loops as phase changers in the elements next to the feeder.

It has already been explained that pseudo half-wave antennae per se are efficient radiators over a fairly wide band of frequencies. Now, in accordance with the teachings of my copending applications, Serial Nos. 12,451 filed March 22, 1935, 18,995 filed April 3, 1935, and 118,886 filed January 2, 1937, the impedances of these antennae may be matched to the impedance of the transmission line at a plurality of frequencies under substantially the conditions herein above assumed. Moreover, by using the procedure explained in my copending application, Serial No. 118,886, it is possible to operate a pseudo half-wave antenna or a number of them on several frequencies simultaneously.

In order that echo phenomena on the longer radio circuits may be reduced it is usually necessary to provide an antenna which is substantially unidirectional. To achieve this end an array of pseudo half-waves may be provided with a reflector. This reflector may be either of the fed or of the parasitic type. When the reflector is fed it is usually made similar to the radiator in every respect and is placed at some fraction of the operating wavelength behind or ahead of the radiator and is fed in such phase that the back radiation is cancelled.

When an array of pseudo half-waves is operated at more than one frequency reflectors of the parasitic type are usually easier to tune, require less material and as a rule provide sufficiently high front to back ratio for practical purposes. For these reasons this type of reflector will be described in some detail.

The parasitic reflector which is well known consists simply of a length of wire placed in back of the radiator anywhere from a $.2\lambda$ to $.3\lambda$ and adjusted to such length that the back radiation from it in the back direction is about 180° out of phase with the radiation from the antenna. Parasitic reflectors of this type are suitable at one frequency only.

A type of parasitic reflector which is suitable for use at several frequencies is shown in Figs. 9 and 10. This reflector consists of a pseudo half-wave antenna 11, a length of transmission line 12 and a number of auxiliary sections 13, 14 of transmission line shunted across the main transmission line. When such a reflector is located a fraction of a wavelength behind the radiator then because of the mutual impedance between them there is produced in the reflector a certain voltage E , referred to some convenient point such as a current loop. This electromotive force in turn produces a current which depends on the total impedance of the reflector. This total impedance consists of two parts: the impedance of reflector itself Z_1 and the impedance of the transmission line Z_2 . At a given frequency the impedance Z_1 remains fixed as long as the pseudo half-wave antenna itself is unchanged. The impedance of the transmission line Z_2 , however, may be varied at will, for example, by varying the position of the short circuiting member 15 in Fig. 10. As Z_2 is varied the current in the reflector is also varied in magnitude as well as in phase, the current following the formula

$$i = \frac{E}{Z_1 - Z_2}$$

Thus by adjusting Z_2 it is possible to produce a current which is of approximately correct phase and amplitude in the reflector provided that voltage E has sufficient magnitude and approximately correct phase. This condition exists when the reflector is located between $.1$ and $.3\lambda$ from the antenna. However, as will be mentioned later certain spacings are preferable to others, moreover, in some cases, depending on the length of the antenna and of the reflector a spacing of somewhat less than $.1\lambda$ may be utilized.

Assuming the induced voltage E is of sufficient magnitude and of such phase that the range of phase adjustment provided by Z_2 is sufficient for producing the current of the correct phase, then it follows that by moving the short 15 in Fig. 11 into various positions any value of Z_2 between $-j\infty$ and $+j\infty$ may be obtained. Thus for a given frequency f_1 the reflector is in adjustment when the short 15 is in some position A. At another frequency f_2 , the reflector is in proper adjustment when the short is in some other position B. If it is desired to have the reflector in adjustment at both frequencies at the same time, the simple short would no longer do as it would have to be in both positions simultaneously. In order that this result may be achieved in effect the system shown in Fig. 9 may be employed. In this figure the short in position A has been replaced by a building out section 13 and the length of the open-ended line 14 is made $\frac{1}{4}\lambda$ at frequency f_1 .

The operation of this structure is as follows: at frequency f_1 the quarter wave line 14 produces a nearly zero impedance at A and thus acts substantially as though there were a physical short at A. This action of the quarter wave line is in no way disturbed by the presence of the building out section 13 since the total impedance obtained by paralleling a finite impedance across a zero impedance is, of course, always zero. For this reason the length of section 13 may be varied at will without in any way disturbing the operation of the tuning of the reflector at frequency f_1 . On the other hand, the impedance Z_2 at the second frequency f_2 may be varied by changing the length of section 12. In fact, the length of this

section may be so adjusted as to produce the same value of Z_2 which would result if there were a physical short in position A. Assuming that the distance between position A and position B in degrees at frequency f_2 is ϕ , and assuming further that λ_1 is the wavelength at frequency f_1 and that λ_2 is the wavelength of frequency f_2 and that the length of section 13 in degrees of frequency f_2 is θ .

Then in order that the impedance at B be equal to zero at frequency f_2 it is necessary that the impedance at A at the same frequency be equal to $-j \cot(90^\circ - \phi)$.

The impedance which is actually obtained at this point is Z which is given by the following equation:

$$(1) \quad \frac{1}{Z} = \frac{1}{j \tan \theta} + \frac{1}{-j \cot(90^\circ - \phi)} = -j \cot \theta + j \tan(90^\circ - \phi)$$

when section 13 has been properly adjusted $Z = -j \cot(90^\circ - \phi)$ so that

$$\frac{1}{Z} = +j \tan(90^\circ - \phi) = -j \cot \theta + j \tan(90^\circ - \phi)$$

This equation enables the calculation of θ for any given

$$\frac{f_2}{f_1}$$

and ϕ . Thus θ may be found from

$$(2) \quad \cot \theta = -\cot \phi + \tan(90^\circ - \phi)$$

The actual length of the section is given by

$$S = \frac{\theta}{360^\circ} \cdot \lambda_2$$

where θ is in degrees and S in same units as λ_2 .

When the reflector is to be tuned to three frequencies there will be three positions of the short which have to be considered. Suppose that these positions for frequencies f_1 , f_2 , f_3 , are respectively A, B and C—Figs. 9 and 11. This tuning may be accomplished as follows: The first step is to determine the points corresponding to A, B and C, at which shorts would properly tune the reflector at the respective frequencies f_1 , f_2 and f_3 . This is done by moving up or down the transmission line of the reflector a short circuiting member, while energizing with the desired frequency the antenna with which the reflector is associated, and at the same time measuring the backward radiation to determine the minimum value. This value shows the proper location for the short circuit. Or conversely the maximum forward radiation may be used to determine this location, if the forward radiation is the prime consideration. The three points A, B and C are then marked on the transmission line.

The next step is to install a quarter wave section at frequency f_1 at A and to calculate the length S of a shorted building out section which connected at point A would tune the reflector to f_2 as has already been explained above. Then instead of installing this shorted building out section of length S an open section of length

$$S + \frac{\lambda_2}{4}$$

is installed. After this is done the reflector will be tuned to two frequencies f_1 and f_2 . Now in order to tune the reflector to the third frequency

5 a section of length D is connected across the section of length

$$S + \frac{\lambda_2}{4}$$

at the point which is

$$\frac{\lambda_2}{4}$$

from the open end of that section. This new section of length D will not disturb the operation of the reflector at frequencies f_1 and f_2 but will permit the tuning at the third frequency.

The length D of the new section may be calculated by assuming for the moment, that only frequencies f_1 and f_3 are concerned. Then the length S' of the building out section which would tune the reflector to frequency f_3 may be calculated from Equation 2.

When this phantom length S' is known, the desired length D may be calculated at once. In fact the impedance presented by the shorted section of length S' at frequency f_3 is equal to

$$j \tan\left(\frac{2\pi}{\lambda_3} S'\right)$$

In order that the complex section consisting

$$\frac{\lambda_2}{4}$$

30 D and θ present the same impedance at frequency f_3 as a simple shorted section of length S' , the following equation must be satisfied

$$35 \quad j \tan\left(\frac{1}{\frac{2\pi}{\lambda_3} S' - \frac{\theta f_3}{f_2}}\right) = \frac{1}{-j \cot(90^\circ - \frac{f_3}{f_2})} + \frac{1}{j \tan\left(\frac{2\pi}{\lambda_3} D\right)}$$

or

$$\cot\left(\frac{2\pi}{\lambda_3} S' - \frac{\theta f_3}{f_2}\right) = -\tan\left(90^\circ - \frac{f_3}{f_2}\right) - \cot\left(\frac{2\pi}{\lambda_3} D\right)$$

and hence

$$40 \quad \cot\left(\frac{2\pi}{\lambda_3} D\right) = -\tan\left(90^\circ - \frac{f_3}{f_2}\right) + \cot\left(\theta \frac{f_3}{f_2} - \frac{2\pi S'}{\lambda_3}\right) \quad (3)$$

from which D may be calculated. When the length D calculated from Equations 2 and 3 comes out longer than a quarter wavelength it may be shortened by a quarter wavelength and left open, instead of shorted at its far end.

So far it has been shown how the reflector may be tuned to a number of different frequencies so that it would produce a maximum amount of forward radiation or a minimum amount of backward radiation for a given position of the reflector with respect to the antenna. As already explained above the voltage which induces a current in the reflector depends in magnitude and phase on the spacing between the reflector and the radiator. While for any given length of the radiator and the reflector there exists the best value of distance between them which results in maximum radiation forward and still another distance between them which results in a maximum amount of back radiation, when the complete aerial consisting of a radiator and a reflector is to be operated at a number of frequencies a compromise must be had.

From experiments with such aerials I have found that in order to obtain a structure which is efficient over a range of frequencies of 2 to 1 it is best to choose such spacing between the reflector and radiator that it is equal to approximately $.2\lambda$ or $.22\lambda$ at the highest frequency at which the aerial is to be operated. Under such

conditions it is found that good reflector action is obtained at twice the said lowest frequency.

The aerial consisting of a radiator and a reflector is not necessarily most efficient when the length of the radiator alone would be most efficient, for example it is found that when the spacing between the reflector and radiator is $.2\lambda$ the aerial is more efficient when both the radiator and the reflector are 1λ long rather than 1.28λ long. On the other hand the latter condition results in greater front to back ratio.

Figs. 12 and 13 in which the abscissa represent the phase angle of Z_1+Z_2 which is the total impedance of the reflector while the ordinates show the field squared which is produced in the forward direction and also in the backward direction. It is seen from Fig. 12 that when the phase angle $Z_1+Z_2=0$ the radiation in a forward direction is a maximum and when the phase angle of $Z_1+Z_2=40^\circ$ the radiation in a backward direction is a minimum. The maximum front to back ratio is obtained with the phase angle of Z_1+Z_2 between these two values.

The maximum radiation forward obtained with the aerial corresponding to Fig. 13 is also obtained when the phase angle of $Z_1+Z_2=0$ but the minimum back radiation occurs when this angle is about 23° . Thus the minimum back condition is more nearly equal to the maximum front condition and a much higher front to back ratio is obtainable with this aerial. The maximum forward radiation obtainable is somewhat less than that obtainable with the antenna corresponding to Fig. 12.

It may be noted that in both cases the condition of maximum forward radiation results in nearly twice the power being radiated in a forward direction clearly showing that with parasitic reflectors much longer than one-half wave length when excited by radiators of the same length it is possible to obtain approximately the same or in fact a better reflector action than is obtainable with a parasitic reflector a half wave length long energized by a half wave antenna well known in the art. It may be seen that the antenna of Fig. 12 when operated at half the frequency becomes a half wave with a reflector located $.1\lambda$ from the radiator and which as is well known can be adjusted to deliver a considerable forward radiation with a high front to back ratio. I have found from experiments that also with radiators and reflectors of lengths intermediate between 1.3λ and $.5\lambda$ it is possible to secure forward gain with a high front to back ratio when the reflector radiator spacing is about $.22\lambda$ at the highest frequency.

At times it may be desired to retune an existing aerial consisting of a pseudo half-wave antenna with a pseudo half-wave reflector of the type herein disclosed at some frequency at which the spacing is greater than $.22\lambda$. Under these conditions it will be found that the reflector can still be tuned so as to increase the forward radiation at the expense of side and back radiation. This action will not, however, be quite as pronounced because of the comparatively low current induced in the reflector.

A number of aerials, each consisting of a pseudo half-wave radiator and a pseudo half-wave reflector may be arranged in broadside or in line and operated as an array. When arranged in broadside it is best to keep the spacing between the ends of the adjacent antennae $.2\lambda$ or greater at the lowest frequency so as to avoid the interaction between the various radiators and reflectors which makes the tuning of the various reflectors dependent on each other and for that reason a somewhat laborious procedure.

While I have described particular embodiments of my invention for the purposes of illustration, it will be understood that various modifications and adaptations thereof may be made within the spirit of the invention as set forth in the appended claims.

For example while in the above description antenna arrangements embodying my invention have been described in connection with transmission the same arrangements may be used for reception of signals. Furthermore while the tuning of the reflector to three different frequencies has been described it should be understood that tuning to more than three frequencies may be carried out by a repetition of the procedure already described.

What I claim is:

40 1. An antenna array comprising a radiator and a reflector, and means for tuning said reflector simultaneously to a plurality of different frequencies, the spacing between said radiator and reflector being not over $.25\lambda$ at the highest frequency and greater than $.08\lambda$ at the lowest frequency.

2. An antenna array comprising a radiator and a reflector, each having two radiating elements of approximately equal lengths, said reflector having a transmission line connected thereto intermediate said lengths, said line terminating in a plurality of auxiliary lines of different lengths, the number of said auxiliary lines being at least equal to the number of frequencies at which it is desired to use the array.

ANDREW ALFORD.
